P. C. Ingersoll

United States Patent Office.

PLATT C. INGERSOLL, OF GREEN POINT, NEW YORK.

Letters Patent No. 99,441, dated February 1, 1870.

IMPROVED CHAIR-BOTTOM.

The Schedule referred to in these Letters Patent and making part of the same

To all whom it may concern:

Be it known that I, PLATT C. INGERSOLL, of Green Point, in the county of Kings, and State of New York, have invented a new and useful Improvement in Chair-Bottoms, of which the following is a full, clear, and exact description, reference being had to the accompanying drawing, forming part of this specification, and in which—

Figure 1 represents a vertical section of a chair with my improved bottom applied thereto, and

Figure 2, an inverted plan of the seat-portion of the chair, in illustration of said improvement.

Figure 3 is a vertical section, through one of the looped metal braces used in the construction of the improved chair-bottom, showing the connection of said brace with the spiral spring and interposed rubber bar.

Similar letters of reference indicate corresponding parts.

This improvement relates to chair-bottoms, the seats or cushions of which are supported by a spring or springs arranged below them, and connected with the frame of the chair; and

The invention consists in a novel combination and arrangement of a central spiral spring, looped metal braces connecting said spring, at its upper end, with the chair frame, and lower metal straps, on which the spring is made to rest, whereby a steady and effective spring-like action is secured to the cushion, and the spring is restrained from shutting down, so as to injure it or produce discomfort to the occupant of the chair; and the invention, in such connection, includes a combination with said spring and metal braces, of rubber bars or strips, arranged within the loops of the braces, and interposed between them and the spring on its outside, to secure a steady action of the braces and spring, and to take up lost motion consequent on the play of the braces.

Referring to the accompanying drawing—

A represents the seat-portion of the frame of the chair, and B, a cushion arranged thereon, and which is supported through the open seat-frame by a cen-

trally-disposed spiral spring, C, of tapering construction, and diminishing in diameter in a downwardly direction, said spring centring in and resting, at its lower end, on metal straps D D, secured at their ends to the chair-frame, and serving to brace the latter, while the upper end of the spring is steadied, and an extended bearing-surface, in connection with it, secured to the cushion, by means of metal braces E E E, fastened at their outer ends to the seat-frame, preferably at its corners or angles, and connected at their inner ends by loops a a a a, with the upper coil of the spring, so that on pressure being brought to bear upon the cushion, the strain will be communicated through the braces to the spring, and the latter be steadied by the braces which play with the spring, and ease its action, also prevent it from shutting down, so as to endanger breakage or produce discomfort to the occupant of the chair.

To render more perfect the connection of the braces with the spring, and take up the lost motion consequent upon the play of the ends of the braces relatively to the movement of the spring, I interpose within each loop a, between it and the outer edge of the upper coil of the spring, a bar or strip, b, of India rubber, which serves to soften the action of the brace, and prevent jar or rattle.

What is here claimed, and desired to be secured by Letters Patent, is—

1. The combination and arrangement, substantially as specified, of the metal braces E E E, formed with loops a a a a at their inner ends, the spiral spring C, and the metal straps D D, with the chair-frame or seat.

2. The arrangement of rubber bars or strips b within the loops a of the braces E, in combination with the spring C and metal straps D, essentially as shown and described.

P. C. INGERSOLL.
